UNITED STATES PATENT OFFICE.

FRANK P. TYE, OF MAYWOOD, ILLINOIS.

GASOLINE-FILLING DEVICE FOR MOTOR VEHICLES.

Application filed November 17, 1923. Serial No. 675,415.

This invention relates to a gasoline filling device for motor vehicles, and more particularly to a filling device for use in connection with tanks which are placed under the seat, as in Ford automobiles.

The object of the invention is to provide a filling device which will permit a gasoline, or other tank, under the seat to be filled without removing the seat or cushion thereon, and which will not in any wise interfere with the comfort of the persons seated thereon.

With the above and other objects in view, the invention consists in certain novel combinations and arrangements in parts to be hereinafter more fully described and claimed.

In the accompanying drawings:

Figure 1 is a fragmentary vertical sectional elevation showing my improved gasoline filling device for motor vehicles applied to a tank positioned beneath the seat.

Figure 2 is a central sectional view of the filling device per se.

Referring to the drawings in detail, in which like reference characters are shown to designate corresponding parts throughout the several views, 10 designates a tank such as the usual gasoline tank used on Ford cars and which is arranged beneath the seat 11 having springs 12 and a felt cushion 13 at the top. An opening is made through the seat and an annular top plate 14 is provided around the opening in the cushion 13 over

or under the covering, but preferably over the same. This plate has a flange 15 extending partly or entirely through and into the opening of the cushion 13, as clearly shown in Figure 1 of the drawings. An annular bottom plate 16 is provided, these plates being bolted through the cushion 13 as indicated at 17, said plates being preferably of circular outline in plan. A filling tube 18 is slidable in the tank 10 as indicated at 19, the tank having a hole in the top provided with a threaded rim or ring 20 in which an externally threaded sleeve 21 is secured, said sleeve having an extension at the bottom providing a bayonet slot 22.

The tube 18 is provided with a lug 23, designed to engage the bayonet slot 22 in the form of a bayonet joint or fastening, so that when the tube 18, which is adapted to freely move up and down in the sleeve 21, is raised, the lug 23 may be engaged with

the slot 22 to support the tube in an elevated position to extend through the opening in the cushion 13 as shown in the full lines of Figure 1 of the drawings. However, by disengaging the lug 23 from the slot 22 and slightly elevating and turning the filling tube 18, the tube may be lowered to the dotted line position shown in Figure 1 of the drawings. The top of the tube 18 is provided with a ring 24, the tube being externally threaded for attachment of the ring and the latter being internally threaded for engagement with the tube. A cap or plug 25 threads in the ring 24 and has a handle 26 by which the tube can be raised or lowered and the plug may be attached or removed.

It will be apparent that when the filling tube 18 is attached to the tank and held in raised position, it will extend through the opening in the seat and cushion. Suitable means may also be provided in the filling tube such as a float gauge to indicate the height of the fuel level in the tank, as is common in the art. Obviously, the seat is free to move up and down and is cushioned around the tube 18, as the latter has no connection with the cushion. The device permits filling of the tank 10 without removing the seat cover or cushion and is therefore especially designed for automobiles such as Ford cars, where the tank is located under the seat. The filling of the tank can be conveniently carried on with a device of this character and without spilling the gasoline.

As will be noted, the filling tube 18 is designed to move up and down in the tank, into operative and inoperative positions for filling or when not in use. The ring 24 is larger than the tube and forms a shoulder to engage the ring 20 or top of tank 10 around the opening therein, so as to prevent the tube dropping into the tank. However, whether the tube is in a raised or lowered position, the comfort of the persons reposed on the seat will not be impaired, since the seat cushion can freely move up and down around the tube.

Having thus described my invention. I claim:

In association with a tank having an interiorly threaded inlet opening and a seat cushioned above the tank and the opening, said seat having a hole positioned over the opening; an exteriorly threaded tubu-

lar member adapted to seat in the inlet opening, said tubular member formed at one end with an extension provided with a slot, a second tubular member adapted to fit snugly and slidably within the first mentioned tubular member, provided adjacent one end with a lug adapted to engage the slot men-

tioned and exteriorly threaded adjacent its other end to receive an interiorly threaded closure cap, and an interiorly threaded closure cap adapted to pass freely through the opening in the seat. 10

In testimony whereof I affix my signature
FRANK P. TYE.
